UNITED STATES PATENT OFFICE.

CHARLES WALCOTT STRATFORD, OF SAN FRANCISCO, CALIFORNIA.

PROCESS OF AND APPARATUS FOR REFINING OILS.

Application filed September 8, 1925. Serial No. 54,947.

The hereinafter described invention relates to the refining of liquid hydrocarbons, although its principles and benefits may be very advantageously applied in handling 5 other liquid substances in effecting their heating and vaporization. Insomuch as my invention has particularly amongst its purposes the handling of liquid hydrocarbons, I will illustrate and describe its embodiment 10 in the well known type of cylindrical oil still now generally in use in oil refineries.

Among the objects of my invention are, keeping the inner cylindrical surface of the still free from carbon deposition by causing 15 the liquid hydrocarbon to move rapidly and continuously over the heated surface of the still, increasing the rate of firing of the still by protecting its bottom as exposed to hot furnace gases with a constantly moving 20 liquid mass, increasing the rate of evaporation of the liquid hydrocarbon per square foot of heating surface exposed, eliminating all scraping devices now used within stills to periodically remove carbon deposition, as 25 well as devices for collecting carbon therein. The accomplishment of these objects enables me to materially increase the capacity or output of the still while preserving 30 the integrity of its metallic surfaces against overheating, effecting economies not now obtainable in refining oil as charged in volume in a still of this type.

My process is distinguished by the fact that I cause a continuous circulation or 35 stirring of the mass or total volume of oil in the still while forcing it to travel at high velocity over the inner heated surface of the still in a rapidly moving sheet while stilling.

This I do by discharging the oil within 40 the still under pressure and with velocity through nozzles against its inner cylindrical surface, a dual movement of the oil in well defined circuits taking place. These two movements of the oil I will term and de- 45 scribe as primary and secondary currents or movements, and I desire it to be understood that the stirring or circulation of the oil in mass and its rapid travel in contact with the inner heated surface of the still is en- 50 tirely the result of the force of its discharge against the still surface without the aid of mechanical mixing devices, the primary current spreading the oil into a rapidly mov- 55 ing liquid sheet in contact with the inner still surface and the secondary current stir- ring it in the mass over said surface. The

oil may also be said to travel in a thin layer in pressure contact with the inner heated surface of the still while circulating there- over.

Many applications in the oil industry for my novel process of and apparatus for circu- 60 lating liquid hydrocarbon in mass within an enclosed heated container and while spreading it in a rapidly moving sheet over 65 the inner heated surface thereof to effect an increased efficiency in its heating and vaporization will make themselves known to those skilled in the art.

In order that a comprehensive understand- 70 ing may be had through the illustrative em- bodiment of my invention herein set out, reference should be made to the accompany- ing drawings in which Fig. 1 is a longitudi- 75 nal section of a cylindrical oil still with heating furnace of the type now generally employed in refining oil. The still is shown fitted with the apparatus of my invention, which involves in the present setting a cen- 80 trifugal pump mounted within the still with suction and discharge pipes. The suction of the pump is set to draw the oil from near its bottom and to create a partial vacuum below the surface of the oil level while the discharge of the pump is connected to a pipe 85 manifold with nozzle outlets directed to dis- charge the oil over and against the bottom of the still.

Fig. 2 is a section taken on line 2—2, Fig. 1, to show the oil discharge manifold and 90 its nozzles and the relation of the nozzles to the inner cylindrical surface of the still.

Fig. 3 is an enlarged sectional view of one 95 of the nozzles in the manifold showing its discharge opening adjacent the inner surface of the still bottom.

Fig. 4 is a diagrammatical view showing generally how the dual movement of the oil is effected within the still by my process. The primary movement of the oil along the 100 inner surface of the cylindrical still at high velocity is denoted by the full line arrows A, while the secondary movement of the oil within the mass is denoted by the dotted line arrows B. The oil level in the still is denot- 105 ed by the line XY.

The result of this twofold oil movement is a rapid heat exchange through the still bottom and high rate of vaporization of the oil while stilling.

In this manner I also overcome all un- 110 desirable localized over heating of the oil

which now takes place in stills which are charged with oil in volume and which is the cause of carbon deposition therein.

In the drawings numeral 10 designates a standard type of enclosed cylindrical container providing an oil still. The still 10 is set over a refractory lined furnace and receives heat against its bottom in the present instance from the hot products of combustion of an oil fire, although heat from any source may be employed so long as the temperature is sufficient to effect the vaporization of the liquid hydrocarbon in the still. The still 10 is provided with an oil filling inlet 11 and valve therefor 12 and a residuum outlet 13 and valve therefor 14. The top of the still 10 has a dome 15 providing an outlet for withdrawing the vapors liberated during the stilling operation. Mounted within the still 10 is pump 16 and mounted on the exterior of the still is electric motor 17. Suitable shaft transmission means connects the pump 16 and the motor 17 through the gland and stuffing box 18. The pump 16 is fitted with the suction pipe 19 and the discharge pipe manifold 20. The discharge manifold 20 comprises an assembly of pipes connected to the discharge side of the pump 16 with headers 21 running laterally of the still 10 and connecting pipes 22 running longitudinally thereof. The headers 21 are so set with reference to the inner surface of the still bottom as to bring the longitudinal pipes 22 into close proximity thereto. Inserted or fitted into the pipes 22 at suitably spaced intervals are nozzles 23. The nozzles 23 provide a means so that oil pumped through the manifold 20 will be discharged against the inner surface of the still 10 with velocity. The number of nozzles employed is governed by the area of the surface over which the oil is desired to be put in motion and the intensity of the liquid movement desired to be effected.

Again, the rapidly moving liquid over the heated surface being the result of the partial vacuum created by the pump and spread of the oil around the outlets of the nozzles, it is obvious that with a given oil discharge pressure the spacing of the nozzles over the surface will govern the continuity of the rapidly moving liquid sheet covering formed over the surface.

It is desired to note that any equivalent form of oil discharge manifold located with nozzles adjacent the inner surface of the still against which it is desired to force the oil therethrough may be used.

In operation the still 10 is first filled with oil through the valve 12 and inlet 11 to a level XY, suitable for stilling, the volume of oil in the still being kept up to such level as desired to suit the stilling operation by regulation of the valve 12, while the residuum outlet from the still 10 is con-

trolled by regulation of the valve 14. Upon starting the motor 17 driving the pump 16 the oil is drawn from the bottom of the still by the pump, thus creating a vacuum below the level of the oil and the oil is forced through the discharge manifold 20 and the nozzles 23 against the inner heated surface of the still bottom 10 thereby effecting the continuous liquid movement of my process.

The embodiment of my invention herein illustrated and described is for the purpose of setting forth its principles and advantages and my invention is by no means limited to this showing.

What I claim is:—

1. The process of refining oil in a still containing a maintained quantity of oil during the stilling operation, which consists in drawing the oil from adjacent the bottom thereof to create a partial vacuum below the oil level, discharging the drawn oil under pressure in a plurality of separated streams against the inner heated surface of the still with such force and in such predetermined relation to each other as to cause each of said streams aided by said partial vacuum to form thin laterally extending, rapidly moving films of oil against the heated still surface and the several films so formed to mutually coact to induce a rapid circulation of the oil upwardly from said heated surface to the top of the oil body and downwardly to points adjacent the heated still surface, whereby to induce a rapid circulation of the entire body of oil within the still and to cause its repeated contact with the more highly heated portions thereof.

2. The process of refining oil in a still containing a maintained quantity of oil during the stilling operation, which consists in continuously drawing the oil from adjacent the heating surface of the still and thereby creating a partial vacuum below the oil level, in discharging the drawn oil in a plurality of separated streams aided by said partial vacuum against said surface under such pressure and in such predetermined relation to each other as to cause each of said streams to form a thin laterally extending, rapidly moving film of oil against the heated still surface and the several films so formed to mutually coact to induce a rapid circulation of oil upwardly from said heated surface toward the top of the oil body and downwardly to points adjacent the heated still surface, whereby to induce a rapid circulation of the entire body of oil within the still and to cause its repeated contact with the more highly heated portions thereof.

3. Apparatus for refining oil comprising a still to contain a maintained quantity of oil during stilling, means to draw oil from adjacent the heated surface of the still and

create a partial vacuum below the level of the oil, and means through which the oil is discharged by said first mentioned means in a plurality of separated streams against the said heated surface with such force and in such predetermined relation to each other as to cause each of said streams aided by said partial vacuum to form a thin laterally extending, rapidly moving film of oil 10 for the purpose specified.

4. Apparatus for refining oil comprising a still to contain a maintained quantity of oil during stilling, means to draw oil from adjacent the heated surface of the still and create a partial vacuum below the level of the oil, pipes, headers connecting the pipes, said pipes and headers being in communication with the first mentioned means and having outlets through which the oil is discharged by said first mentioned means in a plurality of separated streams against the said heated surface with such force and in such predetermined relation to each other as to cause each of said streams aided by said

partial vacuum to form a thin laterally extending, rapidly moving film of oil for the purpose specified. 25

5. Apparatus for refining oil comprising a still to contain a maintained quantity of oil during stilling, a pump to draw oil from adjacent the heated surface of the still and create a partial vacuum below the level of the oil, pipes, headers connecting the pipes, a manifold in communication with the headers and with the pump, the inlet of said pump being below said manifold, said pipes and headers being in communication with the pump and having outlets through which the oil is discharged by said pump in a plurality of separated streams against the said heated surface with such force and in such predetermined relation to each other as to cause each of said streams aided by said partial vacuum to form a thin, laterally extending, rapidly moving film of oil for the purpose specified. 30 35 40 45

CHARLES WALCOTT STRATFORD.
